ATTORNEY.

UNITED STATES PATENT OFFICE.

GEORGE T. WARWICK, OF NEWARK, NEW JERSEY.

BALL-BEARING.

SPECIFICATION forming part of Letters Patent No. 578,049, dated March 2, 1897.

Application filed March 16, 1896. Serial No. 583,367. (No model.)

To all whom it may concern:

Be it known that I, GEORGE T. WARWICK, a subject of the Queen of Great Britain, and a resident of Newark, in the county of Essex 5 and State of New Jersey, have invented certain new and useful Improvements in Ball-Bearings, of which the following is a specification.

This invention relates to improved constructions of ball-bearing mechanism for bicycles and analogous vehicles, the novelties most particularly pertaining to the construction of the parts forming the members between which the balls are comprised and the 10 inclusion within or relative to said parts of a ball-retainer whereby on the removal of one of the members of the bearing the balls will be withheld against spilling, and the constructions and combinations inclusive of the 15 hub, sprocket-wheel, and one of the members of the ball-bearing whereby the said one of the ball-bearing members constitutes the locking device, preventing the sprocket-wheel from becoming detached from the hub, especially at the time of back-pedaling.

The invention consists in the construction and combinations of parts and devices, all substantially as will hereinafter fully appear, and be set forth in the claims.

30 Reference is to be had to the accompanying drawings, in which Figure 1 is a perspective view representing a rear-wheel axle for a bicycle and the hub and sprocket-wheel thereon, the bearing devices appearing as partially and externally exposed. Fig. 2 is a central longitudinal sectional view through the same. Fig. 3 is an outer end view of the ball-case and sprocket-wheel. Fig. 4 is a perspective view of the removable ball-case as seen from the 35 inner end thereof, comprising the ball-retainer. Fig. 5 is a perspective view of the spring ball-retainer.

Similar characters of reference indicate corresponding parts in all of the views, and in 45 the drawings A represents the hub, having within each end portion the internal screw-threads a a^2 for the reception of the correspondingly externally-threaded portions b^2 of the annular ball-cases B B^2 . At its sprocket- 50 receiving end the hub is externally screw-threaded at d reversely of the internal screw-

thread at such end and is also shouldered at f , whereby to receive the hub of the sprocket-wheel C thereon and with its inner end against said shoulder f .

D represents the axle or shaft, and E E^2 are the cones, the one E having a sliding fit on the extremity of the shaft, limited by the shoulder e , while the cone E^2 at the opposite end of the hub screw-threads on the axle.

The balls g are comprised in the annular ball-race constituted by the groove h in the ball-case B or B^2 and the adjacent tapering portion of this cone, which is somewhat widely surrounded by the said ball-case.

The boss or dome-like end 10 of each of the ball-cases terminates or converges in the annular groove 12 and flange 13, and the groove 14 in the flange at the end of the cone receives the said end flange 13 of the ball-case, the 70 outer boundary of the groove 14 in its close relation to the said end flange constituting a good dust-guard.

It will be here pointed out that should water come upon the exterior of the ball-case 75 in running down on the dome-like portion thereof it will upon reaching said groove 12 encounter the flange 13 outside thereof and be prevented from flowing into the interior of the bearings, but will, on the other hand, 80 drop from the groove.

The annular ball-case B or B^2 at its inner end has the seat or shoulder j and the annular groove 15 in the internal wall of the ball-case near said seat.

The ball-retainer comprises an annular shell m , open at both ends and provided with a base-flange m^2 and a spring m^3 for holding the retainer against accidental displacement, although capable of being purposely sprung 90 to permit the removal when desired.

The cone E or E^2 projects into the ball-case from the outer end of the latter, and of course when in its place and adjusted prevents the removal of the balls. The ball-retainer has its base-flange m^2 set upon said seat j in the ball-case, while the annular portion m of the retainer, through which the axle or shaft freely passes, is in proximity to the end of the cone. The distance between the 100 circular end of the retainer and the outer edge of the ball-groove h is somewhat (in prac-

tice very slightly) less than the diameter of the balls. The spring is here shown at m^3 as of round wire bent to comprise the greater portion of a circle and having its ends 18 angularly and rearwardly turned. By having the rear or inner mouth of the ball-case flaring, as seen at 20, such mouth tapering down to the groove 15, the spring may be easily constricted as it is crowded toward the flange m^2 of the retainer, whereby to snap into the said groove 15 therefor, (the depth of which is not necessarily as great as the thickness of the wire from which the spring is made.) The angular end pieces 18 18 serve as finger-lugs to conveniently secure the reconstriction of the spring for its removal. Therefore, of course, when the ball-cases B B² are removed the balls are carried with them without liability of displacement, and yet obviously their removal is readily done at pleasure.

The retainer may be constructed in the form of a very thin light shell spun up or struck up, there being no necessity for great stability or strength, as it has to withstand no pressure and is not at any time liable to sustain injury or distortion. Its presence therefore does not add materially to the weight of the bearing, while the advantage of removing the ball-cases with the balls intact is manifest.

The sprocket-wheel C, screwing with, say, a right-hand thread on the correspondingly-threaded portion of the hub, beds against the said shoulder f of the hub, and the draft of the sprocket-chain for the propulsion of the bicycle, &c., the more tightly sets the sprocket-wheel on the hub. The ball-case B, screwing into the end of the hub with a left-hand or reverse thread, sets up against the outer face or end of the sprocket-wheel and serves as a bed against which the sprocket-wheel sets when the draft of the sprocket-wheel is reversed in back-pedaling, and therefore the provision of the hub having the shoulder f and the reversely-threaded external and internal portions, the sprocket-wheel screwing and setting against the hub-shoulder and the ball-case screwing into the hub and by a proximate portion thereof constituting a check against the loosening of the sprocket-wheel, contemplates a novel arrangement and valuable result, especially in view of the fact that it dispenses with the necessity of a check-nut, the use of which is undesirable, owing to its being an extra cumbrous and weighty part, and because, as plain, the application of the check-nut could not be conveniently made.

The edge portion of the ball-case B is peripherally recessed, or serrated as shown at n , and is overlaid by the widened rim o of the sprocket-wheel. A set-screw t , passing through the widened rim, detachably engages in some of the recesses n and holds the ball-case from turning or being turned to affect the adjustment of the bearings so far as the

same would be affected by the movement of the ball-case. The movement of the one cone at one end of the hub insures the adjustment of the bearings at both ends of the hub.

Having now described my invention, what I claim, and desire to secure by Letters Patent, is—

1. In combination, a hub or corresponding part, a shaft or axle, an annular ball-case removably confined in the hub, and having an internal ball-groove, a cone entering the annular ball-case, the balls and a ball-retainer removably applied within the ball-case, and having a circular edge of such retainer located at a distance from the farther edge of the ball-groove which distance is less than the diameter of the balls, and a spring for confining the retainer in the ball-case, substantially as described. 75

2. In combination, a hub or corresponding part, a shaft or axle, a ball-case, removably confined in the hub, having an internal ball-groove, and having an annular seat back of the ball-groove, a cone and the balls, and a ball-retainer consisting of an annular shell with a base-flange, the latter resting on the said annular seat, while the end of the annular part has a position to so close the annular mouth of the ball-race as to prevent the accidental displacement of the balls, and a means for detachably holding the ball-retainer in its juxtaposition, substantially as described. 80

3. In combination, a hub or corresponding part, a shaft or axle, a ball-case, removably confined in the hub or like part, having an internal ball-groove, an annular seat back of said groove, and a small annular groove back of said seat, a cone and the balls, the annular ball-retaining shell having the flange m^2 to rest on said seat, and the circularly-bent spring m^3 having the angularly-bent finger-lugs 18 18, all arranged substantially as described and shown. 95

4. In combination, a hub or corresponding part, a shaft or axle, a ball-case, removably confined in the hub or like part having an internal ball-groove, an annular seat back of the groove, a small annular groove 15 back of said seat, and said case having its internal wall 20 from said groove rearwardly flaring, a cone and the balls, the annular ball-retaining shell having the flange m^2 to rest on said seat, and the circularly-bent spring adapted by constriction to be snapped into said groove 15, substantially as described and shown. 105

5. In a bicycle or analogous vehicle, in combination, the hub, a sprocket-wheel, externally screwing onto the hub, said sprocket having a flanged rim, the ball-case having the serrated periphery, screwing into the end of the hub, with its said serrated portion within said rim-flange of the sprocket, the balls in said ball-case, and a set-screw passed through the said flange to engagement in one 110

of the peripheral serrations in the ball-case, substantially as described.

6. In a bicycle or analogous vehicle the combination with the annular ball-case having at 5 its outer end the conical or dome-shaped portion 10 which terminates in the groove and end flange, and the balls in said ball-case, of a cone bearing upon the balls through the central opening in the ball-case, and having 10 the annular flange with a groove therein in

which to closely accommodate the end flange on the ball-case, for the purposes set forth.

In testimony that I claim the foregoing as my invention I have signed my name in presence of two witnesses hereto.

GEO. T. WARWICK.
